UNITED STATES PATENT OFFICE.

EDWARD F. DREGER, OF OAKLAND, CALIFORNIA.

BOWLING-ALLEY DRESSER.

SPECIFICATION forming part of Letters Patent No. 756,780, dated April 5, 1904.

Application filed July 23, 1903. Serial No. 166,758. (No model.)

To all whom it may concern:

Be it known that I, EDWARD F. DREGER, a citizen of the United States, residing at 761 Fourteenth street, in the city of Oakland, 5 county of Alameda, and State of California, have invented certain new and useful Improvements in Bowling-Alley Dressers; and I do hereby declare the following to be a full, clear, and exact description of the said invention, 10 such as will enable others skilled in the art to which it most nearly appertains to make, use, and practice the same.

This invention relates to improvements in surface-dressers for bowling-alleys, and particularly to the novel construction and arrangement of the parts.

The object of this invention is to provide means for dressing the surfaces of alleys to remove depressions caused by uneven wear, 20 warping, &c., by planing, sandpapering, and polishing.

The bed of a bowling-alley is composed of laminated strips of timber, usually maple, and varies in width from forty-one to forty-three 25 inches, having the channels on either side in which balls leaving the bed are directed to the pit at the end of the alley. The constant rolling of balls over the bed-surface seek out the softer spots, which are soon worn below 30 the plane of the surface or the whole bed may warp or settle, materially influencing the direction of the balls.

Broadly, the invention consists of a traveling carriage running upon rails parallel with 35 the line of the alley and leveled with the plane thereof, the carriage carrying a revolving head adapted to be fitted with cutting-bits, sandpapering-disks, and waxing and polishing devices to complete the process of refinishing 40 the bowling-surface. The carriage and cutter-head are driven by a suitable motor through the necessary gearing, clutches, &c. The rails upon which the machine travels are 45 adjustably secured to the division-pieces of the alley and are capable of easy and delicate adjustment vertically. The depth of cut made by the cutter-head is determined by a screw adjustment by means of which the said head is raised and lowered with respect to the plane 50 of the bowling-surface.

In the drawings, Figure 1 is a front elevation of a machine constructed in accordance with this invention. Certain of the parts are shown in partial section to better illustrate their construction. Fig. 2 is a plan view from 55 above of the same, the large gear-wheel on the vertical shaft of the cutter-head being omitted to disclose the underlying thrust-block. Fig. 3 is a side elevation of the same.

Similar letters of reference designate similar parts throughout the several views.

In detail the construction consists of the traveling carriage made up of the transverse I-beams A, connected across the ends by the cast bolsters A', and having the truck-brackets 65 A², in which the axles A³ A⁴, carrying the traction-wheels A⁵, are journaled. The cutter-head consists of the disk B, reinforced by the webbed hub B', fixed on the shaft B². The shaft B² revolves in the thrust-block B³, 70 which is hollowed to receive melted Babbitt or some suitable antifriction metal which molds itself about the shaft to receive the thrust of the thrust-flanges B⁴ thereon. The thrust-block B³ is vertically adjustable in the 75 bracket composed of the cross-beam B⁵, fixed between the webs of the I-beams A, the cross-beam B⁶, (coincident,) bolted thereto by the bolts B⁷, being slotted in its connection with the I-beams A to allow for lateral adjustment 80 with the cross-beam B⁶, between which the square thrust-block is adjustably guided. The thrust-block controlling the cutter-head is vertically adjustable by the hand-screw B⁸, 85 threaded in the overhanging bracket B⁹ and stepped in the cross-beam B⁶. The adjustment of the thrust-block is fixed by the set-screw B¹⁰, threaded in the cross-beam. The shaft B² is driven by the bevel-gear B¹¹, feathered on the shaft and resting upon the bridge 90 A⁶, extending across the center of the machine between the I-beams A. The cutter-head shaft is driven by the bevel-gear B¹¹, meshed directly with the pinion C' of the motor C, which is mounted on the carriage between 95 the cross-beams B⁵ and the adjacent I-beam.

The advance of the carriage is synchronized with the rotation of the cutter-head and is propelled by a reduction of speed from the small sprocket C² on the motor-shaft (nine 100

hundred and seventy-five revolutions per minute) transmitting through the sprocket-chain C³ to the large sprocket D, fixed on the short shaft D', revolving in the pillar D², bolted to the frame of the carriage. The small sprocket D³, fixed on the opposite end of the shaft D', transmits the rotation through the sprocket-chain D⁴ to the idler D⁵, loose on the axle A³, and composed of the sprocket-gears D⁶ D⁷.
 10 The sprocket D⁷ transmits through the sprocket-chain D⁸ to the sprocket E' on the end of the shaft E, supported by the pillars E² E³ E⁴ bolted to the frame of the carriage.
 The tractive power is derived from the line-
 15 shaft E, the direction of travel being controlled by the clutch mechanism located between the pillars E³ E⁴ and consisting of the loose pinion E⁵, meshed with the pinion E⁶, fixed on the counter-shaft E⁷ and carrying
 20 the sprocket E⁸, transmitting through the sprocket-chain E⁹ to the sprocket E¹⁰, fixed on the axle A³. From the loose pinion E¹¹ power is transmitted through the sprocket-chain E¹² to the sprocket E¹³, fixed on the axle A³. The direction of travel is determined by throwing the clutch E¹⁴, feathered on the shaft, into engagement respectively with the pinion E⁵ or E¹¹. The clutch is controlled by the lever E¹⁵, pivoted between the pillars E³ E⁴.
 25 30 The traction-rails F are preferably composed of convenient lengths of bulb-angle iron, the flange of which is set in the socket F' and secured by the set-screw F², the socket having the vertical stem F³, extending through the clamp F⁴, where it is pinched by the bolt F⁵. The rails are adjusted to the desired level by the screw threaded in clamp F⁶ and operating against the end of the stem F³. The clamp F⁶ is secured to the division-pieces X' 35 of the alley by the hand-screws F⁷. The division-pieces vary with different construction of alleys, in which event the clamp must be made to conform thereto.
 The first operation is to apply and level the traction-rails the whole length of the alley, then mount the carriage thereon and adjust the cutter-head to remove the desired cut from the surface of the alley-bed. The cutting-bits G consist of a length of steel tube of the desired temper, beveled to an edge to the inner diameter and staggered or set back at an angle to present only a portion of the cutting diameter to give clearance to the bit. The bits are clamped in the bushings G', set through
 40 45 50 the disk B of the cutter-head, and are arranged four in number in about this proportion, the first being from the center of the cutter-head twenty-one inches, the second twenty-one and one-quarter, the third twenty-one and one-half, and the fourth twenty-one and three-quarters. This arrangement of the bits provides for four concentric cuts with each revolution of the cutter-head in a constantly-advancing direction. In addition to
 55 60 65 70 75 80 85 90 95 100 105 110 115 120 125 130 the above arrangement the bits are set at va-

rying depths in rotation, so that the cut from the alley-surface is approached gradually. For instance, if one-quarter of an inch is to be removed the second bit is set one-sixteenth of an inch below the first, and so on. Obviously this arrangement or the number of bits could be varied without departing from the spirit of this invention.

To insure tractive force and steadiness, the whole structure is massive, heavy, and carefully balanced, the weight of the motor being balanced on the opposite of the center by the weight of the operator, who sits on the flooring X³ in reach of the reversing-lever and starting-switch of the motor. Lateral deviation of the carriage is absorbed by the rollers I, adjustably mounted on the carriage and resiliently bearing against the inside of the web of the traction-rails.

After the cutters have passed over the alley-surface the gouging action of the bits has left slight corrugations, which are removed by lifting the bits and inserting in the bushings G² similar to G', the disks H having an abrasive surface bearing against the surface of the alley. After the sandpapering the disks can be removed and polishing-brushes substituted in two of them, while stocks of wax can be placed in the others to bear resiliently against the surface, which has been previously shellacked or treated to take the requisite polish. The changes in the cutter-head can be made while the same is at rest over the pit at the end of the alley.

In professional bowling-alleys it is usual to provide a number of parallel bowling-surfaces. The weight of the machine described necessitates some means for transferring its operations from one surface to another without undue labor. To this end the truck-brackets A² are provided with the studs J, adapted to receive the heads of the levers J', in which the wheels J² are mounted, and which are the fulcrum of the levers J', which being forced down and secured together by the pins J³, extending through both, form a temporary truck upon which the machine may be transversely transported on temporary tracks laid for the purpose. During the operation of the machine the mechanisms just described can be removed.

Having thus described this invention, what is claimed, and desired to be secured by Letters Patent, is—

1. A bowling-alley dresser, consisting of a traveling carriage; traction-rails laid parallel with the line of the alley, and capable of vertical adjustment; a revolving head mounted upon a shaft, engaging a thrust-block capable of vertical adjustment, a motor mounted on said carriage and adapted to rotate said shaft; cutting-bits consisting of sections of tubes sharpened and extending at an angle through the revolving head, at varying distances from the center thereof; a counter-shaft geared to

- the said motor, and to the traction-wheels of the carriage; and suitable clutch mechanisms adapted to control the tractive travel of the carriage; temporary trucks capable of traveling transverse to the normal travel of the carriage, and consisting of levers pivoted to the carriage, and having rollers mounted thereon, and means for locking the levers together in operative position.
2. A bowling-alley dresser comprising a traveling carriage, a motor carried upon the carriage and adapted to drive the same, traction-rails laid parallel with the line of the alley, means for adjusting the same vertically, a revolving head leveled with the plane of the alley and carried by said carriage said head being geared with said motor and provided with dressing devices, and means for absorbing lateral deviation of said carriage.
3. A bowling-alley dresser comprising a traveling carriage, and a revolving dresser-head mounted thereon, both synchronously driven, clamps adapted to embrace the division-pieces of the alley, sockets mounted in said clamps and supporting rails, and means for adjusting said sockets vertically.
4. A bowling-alley dresser consisting of a traveling carriage, a revolving dresser-head mounted thereon, both synchronously driven, traction-wheels for said carriage, means for adjusting the same vertically, and means for absorbing lateral deviation of said carriage.
5. A bowling-alley dresser comprising a traveling carriage, a revolving dresser-head mounted thereon, both synchronously driven, 35 clamps adapted to embrace the division-pieces of the alley, sockets mounted in said clamps and supporting rails, said sockets having depending shanks, adjusting-screws engaging said shanks, and laterally-disposed rollers 40 mounted in resilient bearings and engaging said rails.
6. A bowling-alley dresser comprising a traveling carriage, a revolving dresser-head mounted thereon, both synchronously driven, 45 and temporary trucks arranged to travel transversely to the normal travel of the carriage.
7. A bowling-alley dresser comprising a traveling carriage, a revolving dresser-head mounted thereon, both synchronously driven, 50 levers pivoted to said carriage and extending transversely thereof, and carrying-wheels mounted in said levers.
8. A bowling-alley dresser comprising a traveling carriage, a revolving dresser-head 55 mounted thereon, both synchronously driven, levers pivoted to said carriage and extending transversely thereof, said levers having recesses, carrying-wheels mounted in said recesses, and means for locking the levers together in operative position.
- In testimony whereof I have hereunto set my hand this 4th day of June, 1903.
